(57) **CLAIM**

The ornamental design for a robotic machine unit for automated vacuum mooring, as shown and described.

DESCRIPTION

Fig. 4.1 is a top, front perspective view of a robotic machine unit for automated vacuum mooring;

Fig. 4.2 is a front elevation view thereof;

Fig. 4.3 is a top, back perspective view thereof;

Fig. 4.4 is a right-side view thereof; and

Fig. 4.5 is a right-side view thereof in an alternate condition of use; and

Fig. 4.6 is a right-side view thereof in another alternate condition of use.
